(57) **CLAIM**

The ornamental design for a hair trimmer, as shown and described.

DESCRIPTION

FIG. 1 is a perspective view of a hair trimmer showing a new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof;

FIG. 7 is another perspective view thereof, showing a portion of the front, left side, and bottom thereof;

FIG. 8 is another perspective view thereof, showing a portion of the rear, right side, and bottom thereof; and,

FIG. 9 is another perspective view thereof, shown a portion of the rear, right side, and bottom thereof.

The broken lines shown in the drawings illustrate portions of the hair trimmer and form no part of the claimed design.
